UNITED STATES PATENT OFFICE.

CHARLES F. MURDOCK, OF DETROIT, MICHIGAN, ASSIGNOR OF ONE-HALF
TO JONATHAN K. WEBSTER, OF SAME PLACE.

DYNAMOMETER.

SPECIFICATION forming part of Letters Patent No. 380,294, dated March 27, 1888.

Application filed September 10, 1885. Renewed November 12, 1887. Serial No. 254,981. (No model.)

To all whom it may concern:

Be it known that I, CHARLES F. MURDOCK, of Detroit, in the county of Wayne and State of Michigan, have invented new and useful Improvements in Dynamometers; and I do hereby declare that the following is a full, clear, and exact description thereof, reference being had to the accompanying drawings, which form a part of this specification.

10 This invention relates to a new and useful improvement in dynamometers, especially designed to readily ascertain the force required in driving the machines in an industrial establishment. The dynamometer herein described 15 belongs to that class in which a spring forms the medium for transmitting the power, and wherein the state of tension of said spring is indicated on a scale on which are marked the degrees of static force corresponding to the 20 tension of the springs.

My improvement consists in the peculiar arrangement and construction of the parts, all as hereinafter described, and pointed out in the claims.

25 In the drawings which accompany this specification, Figure 1 is a perspective view of my improved dynamometer. Fig. 2 is a similar perspective view, looking at the opposite side, and with some portions broken off or removed.

30 Fig. 3 is a vertical central section.

A is the counter-shaft from which the power for driving the machinery is obtained. Upon this counter-shaft is secured the hollow shaft B, and upon this is sleeved a loose pulley, C, 35 which is held between two collars, D E, made fast upon the shaft B. The pulley is provided with a hub, B', and a coil-spring, F, is sleeved upon the hub on one side of the pulley, with one end secured to the pulley at a and the 40 other to the collar E at b.

H is a looser ring seated in an annular groove formed upon the hub of the pulley on the side opposite to where the coil-spring is placed. It is also provided upon its annular face with a 45 pin or projection, I, and with a pointer, J, for indicating the position of this loose ring upon a scale, K, with which the adjoining part of the hub of the pulley is provided.

L is an arm secured to the periphery of the

collar D, and adapted to engage upon its free 50 end with the pin I on the loose ring H, as shown in Fig. 1.

M is a cap or cover for the dynamometer-spring F. It is secured in any suitable manner to the collar E, as shown in Fig. 3, while 55 in Fig. 2 it is shown detached.

In practice, when power is applied to the shaft A and a resistance to the face of the pulley C, (said resistance being furnished by the drive-belt,) the dynamometer-spring F is put 60 under tension, as it forms the medium between the power and the resistance. The degree of the tension required to overcome the resistance is indicated by the pointer J upon the scale K, for it will be seen that the loose ring H, which 65 carries the pointer, is turned in a degree corresponding to the tension of the spring by means of the engagement of the arm L with the pin I.

The loose ring H may be provided with a 70 suitable tension device—such as the screw c—to give it a little friction on its seat, so as to prevent its accidental displacement, without, however, offering any resistance to its turning freely whenever the arm L strikes against the 75 pin I. The scale K is arranged to indicate the degrees of static force corresponding to different states of tension of the spring F.

It is obvious that if there is any fluctuation in the power required to overcome the resistance the pointer J indicates the maximum of power.

The "dynamometric pulley," as my device may be properly called, can be readily applied to counter-shafts of different size by making 85 the bore of the shaft B to correspond; but it is obvious that the shaft B may form an integral part of the shaft A as far as the operation is concerned.

The collars D and E are preferably removably secured upon the shaft B by suitable set-screws, or otherwise, so as to admit of adjusting the parts and facilitating the mounting or dismounting of the device. The cap M protects the dynamometer-spring from accidental 95 injury.

In adjusting the device for taking a reading the loose ring H ought to be turned to bring

the pin I in contact with the arm L. The dynamometer-spring is preferably of such power that its torsional range is only the arc of a circle.

My device is very simple. Its constructive form is very suitable for having the pulley well balanced. It does not form a charge upon the power. It is of so compact form that it may take the place of an ordinary pulley, and it can be read when the machinery is at rest.

10. What I claim as my invention is—

15. 1. In a dynamometer, the combination of a loose pulley provided with a hub, of a dynamometer coil-spring placed concentric to the shaft and forming the medium for transmitting by its torsional tension the power from the shaft to the pulley, of an annular scale on the hub of the pulley, and of a pointer carried by the shaft, so as to indicate the degree of torsion of the dynamometer-spring, all arranged substantially as described.

20. 2. In a dynamometer, the combination, with a loose pulley, a shaft, and a coil-spring, which forms the means of transmitting the power from the shaft to the pulley, of an indicator con-

sisting of the arm L, a collar on the shaft, a 25 hub on the pulley, the loose ring H, the pin I, pointer J, and the annular scale K on the hub of the pulley, all arranged and operating substantially as described.

3. In a dynamometer, the combination of the 30 loose pulley C, the collars D E, fast upon the shaft, the coil-spring F, secured at one end to the collar E and at the other to the pulley, the arm L, secured to the collar D, and the loose ring H, having pointer J and pin I, and the 35 annular scale on the hub of the pulley, all arranged substantially as described.

4. The combination, with the shaft A, the hollow shaft B, loose pulley C, having a hub, collar E on said hub, and the coil-spring F, 40 placed around the hub of the said pulley, of the cap M, inclosing said spring and collar, substantially as described.

CHARLES F. MURDOCK.
